UNITED STATES PATENT OFFICE.

ALONZO D. MURRAY, OF BOSTON, MASSACHUSETTS.

SHIRT-BOSOM ADJUSTER.

SPECIFICATION forming part of Letters Patent No. 634,017, dated October 3, 1899.

Application filed March 16, 1899. Serial No. 709,330. (No model.)

To all whom it may concern:

Be it known that I, ALONZO D. MURRAY, a citizen of the United States of America, residing at Boston, in the county of Suffolk and State of Massachusetts, have invented certain new and useful Improvements in Shirt-Bosom Adjusters, of which the following is a specification.

My invention is designed to provide an attachment for suspenders which will hold in place in a smooth unwrinkled position the shirt-bosom; and to this end I provide an attachment adapted to be adjustably secured to the rear of the suspenders and to extend laterally therefrom around the body of the wearer, with ends for engaging the shirt-bosom.

The invention is illustrated in the accompanying drawing, in which the figure shows a pair of suspenders with the attachment secured thereto.

The suspenders herein shown is a representative of any well-known or improved form, having rear tabs 1 and front tabs 2. The shoulder-straps 3 are connected to the rear tabs by a straight portion 4, to which the attachment is secured. This attachment consists of the tapes 5, extending laterally on

each side of the portion 4 and secured thereto adjustably by a clasp 6. Each tape 4 may be shortened and lengthened by means of a clasp 7, and at its end it carries a loop which engages the central portion of an elastic cord, the latter having an ordinary fastening-clip 9 secured to each end thereof.

The adjustment of the clasp 6 along the portion 4 provides for the comfortable fitting of the device in accordance with the requirements of the wearer.

The clips 9 are attached to the opposite edges of the shirt-bosom and hold the same in place.

What I claim is—

In combination with the suspenders, an interposed piece 4 at the back thereof extending vertically, a band adjustably supported on said interposed piece to be moved up and down thereon, said band having devices at its ends to engage the shirt-bosom, substantially as described.

In testimony whereof I affix my signature in presence of two witnesses.

ALONZO D. MURRAY.
